UNITED STATES PATENT OFFICE.

DAVID S. STEWART, OF MORRIS, WISCONSIN.

TRACTION-ENGINE.

SPECIFICATION forming part of Letters Patent No. 484,828, dated October 25, 1892.

Application filed December 21, 1891. Serial No. 415,712. (No model.)

To all whom it may concern:

Be it known that I, DAVID S. STEWART, a citizen of the United States, and a resident of Morris, in the county of Shawano, and in the State of Wisconsin, have invented certain new and useful Improvements in Traction-Engines; and I do hereby declare that the following is a full, clear, and exact description thereof.

10 My invention relates to certain new and useful improvements in traction-engines; and it consists in the matters hereinafter described, and pointed out in the appended claims.

The invention relates more particularly to 15 an improved form of traction-engine adapted for use in doing heavy hauling, such as for logging and similar purposes, capable of being used in all kinds of weather and upon all kinds of roads.

20 In the accompanying drawings, illustrating my invention, Figure 1 is a side elevation, partly in section, of a traction-engine embodying my invention. Fig. 2 is a longitudinal horizontal section of the same, taken on line 2 2 of Fig. 1. Fig. 3 is a transverse vertical section of my improved traction-engine, taken through one of the trucks. Fig. 4 is a detail view of one portion of my improved apparatus.

25 In said drawings, A represents the boiler of my improved traction-engine; A', the fireman's cab; B B, the truck-frames; C C, the axles of the traction-wheels, and D D supports for the boiler A, pivotally engaged with the 30 central portions of the axles C C.

E E are the traction-wheels, and F F are traction-chains trained over said wheels E E and wheels G and G', respectively. Each of the trucks is provided with one of the axles.

35 C, a traction-wheel E, located upon each end of said axle, a chain F, trained over said traction-wheel, and wheels G and G', over which said chains are also trained. Upon the inner end of the shaft g of each of the wheels G is located a suitable gear-wheel H, which is operatively engaged in any desired manner with suitable driving mechanism. In the particular form illustrated in the drawings this gear-wheel H is arranged to mesh with a pin-

40 ion h, located upon the outer end of a shaft I, upon the inner end of which is provided a bevel-gear I', meshing in turn with a bevel-pinion J, which is located upon a shaft j, to 45 which power is applied in any desired man-

ner. As illustrated in the drawings, each of 55 the shafts j of the front truck is connected at one end by means of a universal joint L with a revolute shaft extending diagonally between the front and rear trucks and similarly engaged with the shaft j upon the opposite 60 side of the rear truck. These revolute diagonally-extending shafts each comprise an angular shaft or rod K, having a sliding engagement at its front and rear ends with correspondingly-shaped tubular sections K' K', 65 as shown more particularly in Fig. 2. To the forward ends of said shafts j j on the front truck are secured by similar universal connections L' L' revolute angular shafts M M, engaged with correspondingly-shaped tubular sections M' M', which are in turn engaged by universal joints m m with suitable crank or driving shafts N N, driven by suitable engines O O, preferably located upon a platform S at the front end of the boiler and supplied with steam from the boiler by a pipe o.

70 At convenient points on the crank-shafts N N are located wheels P P, between which is suitably supported a sliding bar or rod R, carrying brake-shoes adapted to engage with 75 the peripheries of said wheels P P, and adapted to be moved by a lever Q, so as to bring either of said shoes into operative engagement with one of the wheels P.

75 As shown in the drawings, the wheels G G upon each truck are actuated by the driving mechanism to drive the traction-chains F F, the wheels E E running loosely upon the ends of the axles C C and the wheels G' G' being arranged to run as idlers and simply serving 80 to hold the chains F F in proper position and sufficiently taut to secure the proper operation of said chains.

85 Any convenient form of traction-chains may be employed; but I prefer to construct 90 these chains with suitable traction-teeth and with links adapted to engage with teeth upon the wheels G G and G' G'. If desired, the wheels E E may also be provided with teeth; but I prefer to provide said wheels with 95 grooves e e in their peripheries, in which said chains lie. The idler-gears G' G' are preferably mounted on stud-shafts g' g', which are journaled in sliding boxes g' g', which are pressed away from the other wheels G G by 100 springs or cushions g' g'.

105 Any suitable means may be provided for preventing vertical play or oscillation of the

trucks beneath the boiler A—as, for instance, as illustrated in the drawings, in which a stirrup or support T is arranged to depend from the lower side of the boiler and is engaged at its lower side with an eye or loop t upon the frame of the truck. The stirrup or support T, at its lower side where it engages with the eye or loop t, is formed into an arc concentric with the pivotal supports D of the boiler upon the axle C, so as to permit a lateral oscillation of the truck beneath the boiler.

The operation of my improved device is as follows: The operator upon the front platform S runs the engines O O so as to rotate the crank-shafts N N in opposite directions, as shown by the arrows in Figs. 2 and 4, and motion is communicated through the universal connections m m, shafts M' M and M' M', and universal connections L' L' to the shafts j j of the front truck. The pinions J J, carried by said shafts j j, are thereby actuated, and they drive the bevel-gears I' I' and the shafts I I, carrying the pinions h h, which in turn drive the wheels H upon the axles of the wheels G G. This operation transmits motion to each of the traction-chains F F upon the front truck over gears G, G', and E. By the diagonally-arranged shafts K' K and K 30, together with their universal-joint connections with the shafts j j upon opposite sides of the front and rear trucks, motion is transmitted from the gearing upon each side of the front truck to the gearing upon the opposite side of the rear truck, the arrangement of the wheels G, G', and E being the same upon both front and rear trucks. A uniform forward movement is thus given to all the traction-chains F F to propel the vehicle straight ahead. If it is desired to turn the machine to one side, the engine O upon the side toward which it is desired to turn is either stopped or retarded in its motion, the engine upon the opposite side of the platform being permitted to continue its movement. This operation serves to retard the movement of the traction mechanism upon one side of the forward truck and the traction mechanism upon the opposite side of the rear truck, the remaining portions of the mechanism continuing their movement as before. The trucks will thereby be caused to turn at different angles to the boiler, so as to run the one toward the right and the other toward the left, thus enabling the machine to be turned in a very limited space. By the arrangement of the diagonal shafts K K', as before described, the same being composed of sections slidingly engaged with each other, said diagonal shafts are adapted to automatically adjust themselves to the positions of the trucks in an obvious manner. Similarly the shafts M M' are automatically lengthened or shortened when the trucks are turned, so as to correspond with the positions of the trucks. Any convenient means for retarding the motion of the engine O at either side of

the platform S may be provided, that illustrated in the drawings and herein described being a simple form of brake mechanism adapted to be thrown into engagement with either one of the wheels P P upon the crank-shafts of said engines, as may be desired.

By my construction of the traction mechanism, as before described, the toothed chains F F are adapted to engage very firmly with the surface of the ground, and any accumulation of dirt or of snow and ice which may adhere to the chains will be pushed out of the links by the teeth of the wheels G G G and G' G' as the chains pass over said wheels, the traction-chains being thereby kept clean and prevented from clogging, this clogging or filling up of the traction-teeth being a very great defect found in devices of this nature as heretofore constructed.

My improved form of traction-engine is very easily operated, and, by the arrangement of the driving-chains and the traction mechanism for actuating the same, is adapted to be used upon roads where devices of ordinary construction could not be used, while by the arrangement of the power-transmitting mechanism the machine is particularly adapted for turning in very small spaces.

If desired, but one of the trucks may be provided with traction mechanism and the other truck arranged to trail after it.

Many of the details of construction may be variously modified without in any way affecting the merits of my invention, and I therefore do not desire to limit myself to the exact form of construction shown and described.

Having thus described my invention, what I claim is—

1. In a traction-engine, one or more trucks, each provided with a single traction-wheel upon each side, traction-chains trained over said traction-wheels, and means for giving independent longitudinal motion to said chains, substantially as set forth.

2. A traction-engine comprising one or more trucks, each provided with a single traction-wheel upon each side thereof, traction-chains trained over said traction-wheels, and driving mechanism comprising suitable gearing and independently actuated sprocket-wheels adapted to engage with said traction-chains and to give a longitudinal movement thereto, substantially as set forth.

3. In a traction-engine, a truck pivotally engaged with the boiler-support, traction-wheels located upon opposite sides of said truck, sprocket-wheels located in advance and in rear thereof, traction-chains trained over said traction and sprocket wheels upon each side of said truck, and means for giving an independent rotation to one of the sprocket-wheels upon each side of the truck, substantially as for the purposes set forth.

4. In a traction-engine, a truck pivotally engaged with the boiler-support, said truck being provided upon each side with a traction-wheel loosely mounted upon an axle, said

traction-wheels being provided with peripheral grooves or channels, toothed traction-chains trained over said wheels and arranged to lie within said grooves or channels, sprocket-wheels located in advance and in rear of said traction-wheels and engaging with said chains, and suitable means for giving independent rotation to one of said sprocket-wheels upon each side of the truck, substantially as set forth.

5. In a traction-engine, a truck pivotally engaged with the boiler-support, said truck being provided on each side with a traction-wheel loosely mounted upon an axle, said traction-wheels being provided with peripheral grooves or channels, toothed traction-chains trained over said wheels and arranged to lie within said grooves or channels, sprocket-wheels located in advance and in rear of said traction-wheels and engaging with said chains, one of said sprocket-wheels upon each side of the truck being mounted upon a stud-shaft slidably engaged with the truck-frame, and suitable means for giving independent rotation 25 to the other sprocket-wheel upon each side of the truck, substantially as set forth.

6. A traction-engine comprising trucks pivotally engaged with the boiler-supports, each of said trucks provided with independently-actuated traction devices upon its opposite sides, and mechanism for transmitting motion from the traction device upon each side of one truck to the traction device upon the opposite side of the adjacent truck, substantially as set forth.

7. A traction-engine comprising trucks pivotally engaged with the boiler-supports, each of said trucks provided with independently-actuated traction devices upon its opposite sides, and mechanism for transmitting motion from the traction device upon each side of one truck to the traction device upon the opposite side of the adjacent truck, said mechanism comprising revoluble shafts composed 45 of two or more sections slidably engaged with each other and having universal-joint connections with said traction devices at its front and rear ends, substantially as set forth.

8. A traction-engine comprising trucks pivotally engaged with the boiler-supports, each of said trucks provided with independently-actuated traction devices upon its opposite sides, mechanism for transmitting motion from the traction device upon each side of one truck to the traction device upon the opposite side of the adjacent truck, and means for preventing vertical oscillation or play of said trucks, substantially as described.

9. In a traction-engine, the combination, 60 with the boiler and a truck pivotally engaged therewith, of a platform secured to the boiler and provided with independently-operating engines, independent traction devices located upon opposite sides of said truck, and flexible connections between said independent engines and said traction devices, substantially as described.

10. In a traction-engine, the combination, with the boiler and a truck pivotally engaged therewith, of a platform secured to the boiler 70 and provided with independently-operating engines, independent traction devices located upon opposite sides of said truck, flexible connections between said independent engines and said traction devices, and means 75 for retarding the motion of one of said engines without affecting the operation of the other, substantially as described.

11. A traction-engine comprising trucks pivotally engaged with the boiler-supports, each 80 of said trucks provided with independently-actuated traction devices upon its opposite sides, mechanism for transmitting motion from the traction device upon each side of one truck to the traction device upon the opposite side of the adjacent truck, a platform secured to the boiler and provided with independently-operating engines, and flexible connections between said engines and the traction mechanism upon one of said trucks, substantially as described.

12. In a traction-engine, the combination, with the boiler and a truck pivotally engaged therewith, of a platform secured to the boiler and provided with independently-operating 95 engines, independent traction devices located upon opposite sides of said truck, flexible connections between said independent engines and said traction devices, and a reciprocating bar provided with friction devices at its 100 opposite ends adapted for engagement with the engine upon either side of the platform, and a lever for throwing said friction devices into or out of operation, substantially as described.

13. A traction device for road-engines, comprising a traction-wheel, sprocket-wheels arranged to revolve in the same plane with and upon opposite sides of said traction-wheel, one of said sprocket-wheels being operatively 110 engaged with suitable driving mechanism, and a traction-chain trained over said traction and sprocket wheels, substantially as set forth.

14. A traction device for road-engines, comprising a traction-wheel loosely journaled upon an axle and provided with a circumferential groove, two sprocket-wheels arranged to revolve in the same plane with but upon opposite sides of said traction-wheel and one 120 of said sprocket-wheels being operatively engaged with suitable driving mechanism, and a traction-chain trained over said traction and sprocket wheels, substantially as set forth.

In testimony that I claim the foregoing I have hereunto set my hand, at Morris, in the county of Shawano and State of Wisconsin, in the presence of two witnesses.

DAVID S. STEWART.
